UNITED STATES PATENT OFFICE.

FRANK SCHUH, OF TRENTON, NEW JERSEY.

WATER-CLOSET.

1,273,415.

Specification of Letters Patent. Patented July 23, 1918.

Application filed August 30, 1917. Serial No. 188,987.

To all whom it may concern:

Be it known that I, FRANK SCHUH, a citizen of the United States, and a resident of Trenton, in the county of Mercer and State of New Jersey, have invented a new and Improved Water-Closet, of which the following is a full, clear, and exact description.

The invention relates to water closets using compressed air for the forcible ejection of the water from a tank into the bowl.

The object of the invention is to provide a new and improved water closet arranged to occupy a small amount of space, to insure efficient and thorough flushing of the bowl, and to allow use of the water closet with a high or low pressure source of water supply.

Another object is to facilitate the siphoning action of the bowl and to provide a relief valve in the water tank to insure complete discharge of the last portion of the water in the lower portion of the tank and to conduct such water into the bowl to raise the level of the water therein.

A further object is to provide a water closet which can be set on a floor or attached to a wall a distance above the floor.

In order to accomplish the desired result use is made of a bowl having a flushing rim, a closed water tank, a compressed air chamber below the said water tank, a connection between the said water tank and the said air chamber, and a valve mechanism connected with a source of water supply and adapted to connect the said water tank with the water supply, and to connect the water tank with the flushing rim.

A practical embodiment of the invention is represented in the accompanying drawings forming a part of this specification, in which similar characters of reference indicate corresponding parts in all the views.

Figure 1 is a sectional side elevation of the water closet with the seat in closed position and the water filling the water tank;

Fig. 2 is an enlarged sectional side elevation of part of the same with the seat raised and the water flowing from the water tank into the bowl;

Fig. 3 is an enlarged cross section of the air chamber, part of the water tank and the water supply pipe, the section being on the line 3—3 of Fig. 1;

Fig. 4 is an enlarged sectional plan view of the valve mechanism on the line 4—4 of Fig. 1;

Fig. 5 is an enlarged sectional plan view

of the valve mechanism, the bowl and the inlet chamber for the bowl, the section being on the line 5—5 of Fig. 2; and

Fig. 6 is a cross section of the water closet on the line 6—6 of Fig. 1.

The bowl A of the water closet is provided with the usual flushing rim B and the bottom of the bowl A is connected by a water seal or siphon C with the reduced outlet D arranged in the base or bottom E. The leg C' of the siphon C is inclined upwardly and rearwardly and the leg C² of the siphon is of flat oval shape at the dam or mouth C³ and is enlarged from the dam or mouth downward to the reduced outlet D. Owing to the narrow dam or mouth, a comparatively little amount of water is required to start the siphon and as the water after leaving the dam or mouth C³ can readily spread a quick and positive siphoning action is had. In order to render the siphoning action comparatively noiseless, a deflecting rib C⁴ is arranged in the left wall of the leg C² to deflect the down rushing water to the right into the enlarged lower portion of the leg C² and which lower portion is connected at its left with the outlet D. The water is thus conducted in a lateral direction to the outlet D instead of dropping directly down into it from the dam or mouth C³. The several parts mentioned are integrally connected with a water tank F and with a compressed air chamber G arranged below the water tank F, the latter and the said air chamber G being located in the rear of the bowl A, as plainly indicated in Figs. 1 and 2. The rear wall of the integral single-piece structure thus far described is disposed vertically to allow of snugly setting the structure against the wall of a building, or fastening it to such wall, if desired, with the bottom E above the floor. The said rear wall is provided with a manhole F' to permit of obtaining access to the interior of the tank F whenever it is desired to do so.

The bowl A is provided with a seat H hinged at H' to the front of the upper portion of the water tank F, and the said seat H, as shown, controls a valve mechanism I, which latter, however, may be actuated by hand and located within reach of the user. The valve mechanism I is arranged in an inlet chamber J preferably located between the back of the bowl A and the lower portion of the water tank F and integral with the same, and the said inlet chamber

J is connected at its upper portion with the flushing rim B to supply the latter with water, as hereinafter more fully explained. The valve mechanism I is connected with a water supply pipe K and controls the inflow of the water from the supply pipe K into the water tank F; and it also controls the flow of water from the tank F to the inlet chamber J of the flushing rim B. An air pipe L connects the upper portion of the water tank F with the compressed air chamber G so that when the tank F fills with water the air in the tank F is forced by way of the pipe L into the chamber G and compressed therein.

The valve mechanism I is constructed as follows:

Within the inlet chamber J is arranged a vertically disposed tubular casing N, the lower end of which extends through the bottom of the chamber J into the lower portion of the water tank F, and on the said lower end of the casing N is secured a cap O terminating in a nipple O' coupled to the water supply pipe K. The bottom of the casing N is provided with an inlet port P opening into the cap O, and the said port P is controlled by a valve Q held on the lower end of a valve stem Q' extending centrally in the casing N. The lower portion of the casing N and the cap O are provided at the sides with registering inlet and outlet ports P' (see Fig. 4) which connect the interior of the lower end of the casing N with the interior of the water tank F. An outlet port P² is arranged in the side of the casing N a distance above the ports P', and this outlet port P² connects the interior of the lower portion of the casing N with the inlet chamber J. On the valve stem Q' is secured a piston valve Q² fitting the lower portion of the casing N and controlling the port P². The valves Q and Q² are so arranged that when the valve Q² closes the port P², as shown in Fig. 1, then the valve Q is in open position relative to the port P to allow the water to flow through the supply pipe K and ports P, P' into the tank F to fill the latter. When the valves Q and Q² are in the position shown in Fig. 2, the valve Q² is above the port P² and the latter is open, while the valve Q closes the port P, and thus shuts off the water flowing from the supply pipe K into the tank F. The water in the tank F now flows by way of the ports P', P² into the inlet chamber J to pass to the flushing rim B with a view to flush the bowl A. Within the casing N above the valve Q² is arranged a horizontal partition N' on which rests the lower end of a spring R pressing with its upper end against a collar Q³ fixed to the stem Q' carrying the valve Q and Q². The upper end Q⁴ of the valve stem Q' slidably engages a top cap N² of the casing N, and

the upper surface of the end Q⁴ is engaged by a ball S held in a bearing S' attached to the under side of the seat H at the rear portion thereof. Normally the spring R holds the valves Q and Q² in uppermost position, as shown in Fig. 2, and at the same time holds the seat H raised, and when the seat is occupied by a person and swung downward into the position shown in Fig. 1 then the stem Q' is pressed downward against the tension of the spring R and the valves Q and Q² are moved into the position shown in Fig. 1. As soon as the occupant leaves the seat H the latter swings back into the uppermost position by the action of the spring R pressing the valve stem Q' so that the valves Q and Q² return to normal position, as shown in Fig. 2.

From the bottom of the inlet chamber J leads a drainage channel J' into the bowl A to completely drain the water out of the said chamber J. The chamber J is also connected at its bottom by a channel J² with the bottom of the water seal C so that a portion of the water passing into the inlet chamber J flows down the channel J² and into the water seal C to dislodge any sediment that may be in the bottom of the said seal. By reference to Fig. 1 it will be seen that the outlet portion of the channel J² is in an upward and rearward direction so as to force the water upwardly and rearwardly in the seal C.

The water supply pipe K is made in sections connected with each other by a coupling K' attached to one of the sides of the tank F (see Fig. 3) and the outer section of the supply pipe K connects with a water main in the usual manner.

The casing N is provided with an annular seat N³ immediately below the port P² so that when the valve Q² moves into lowermost position it seats itself on the said seat to tightly shut off the water to the port P².

The casing N is preferably provided with an outside shell or covering and the upper end of the casing is provided with an annular flange N⁴ seated on a gasket T held in an annular rabbet or recess J³ formed in the top of the chamber J. A gasket T' abuts against the under side of the bottom of the chamber J and this gasket is engaged by a flange O² formed on the cap O so that when the latter is screwed up on the casing N it draws the flange N⁴ in firm contact with the gasket T and the flange O² moves in firm contact with the gasket T' so that the casing N is securely held in position in the chamber J and leakage is prevented at the upper and lower joints of the casing N with the top and bottom of the chamber J.

In order to insure a proper filling of the water tank F from the lower portion of the valve chamber J, use is made of a safety or drainage valve V arranged in the wall

of the drainage channel J^2 and having a float V' extending in the water tank F . The float V' closes the valve V as soon as the water level in the tank F reaches a predetermined height, and hence the water is not liable to overflow into the air pipe L . When the water is drawn out of the tank F to flush the bowl A the valve V opens by the downward swinging of the float V and the tank F is consequently drained of practically its whole amount of water by way of the drainage channel J^2 . The water passing from the tank F into the bowl A by way of the channel J raises the level of the water in the bowl to the overflow point at the mouth of the siphon.

A plug W is arranged in one side of the compressed air chamber G to drain the latter of any moisture that may have accumulated therein.

Normally the water tank F is practically empty as the valve mechanism I is then in the position shown in Fig. 2 with the valve Q in closed position and the valve Q^2 in open position, as previously explained, to allow water to flow from the tank F by way of the ports P' , P^2 into the inlet chamber J from which the water passes into the bowl, as above set forth. When the seat H is occupied and consequently swung downward then the valves Q and Q^2 move into the position shown in Fig. 1 whereby the port P^2 is closed while the port P is opened to allow the water to flow from the supply pipe K by way of the ports P and P' into the tank F to fill the same. As the water rises in the tank F the air in the top thereof is forced through the pipe L into the compressed air chamber G and compressed therein. When the said seat H is released and the parts returned to normal position as shown in Fig. 2 then the water flows out of the tank F into the bowl as previously explained, with the aid of the compressed air, so that a very efficient and thorough flushing of the bowl takes place as the water is under pressure during the outflow from the tank F .

It will be noticed that by making the bowl A , the siphon C , the compressed air chamber G , the valve chamber J and the tank F integral, a very simple structure is obtained, completely free of joints liable to leak. By locating the compressed air chamber G in the lower portion of the structure the height of the structure is greatly re-

duced so that the structure takes up comparatively little room.

Having thus described my invention, I claim as new and desire to secure by Letters Patent:—

1. A water closet, comprising a bowl having a flushing rim, a closed water tank, a compressed air chamber below the said water tank, a connection between the top of the said water tank and the said air chamber, and a valve mechanism connected with a source of water supply and adapted to connect the said water tank with the said bowl.

2. A water closet, comprising a bowl having a flushing rim, a closed water tank, a compressed air chamber below the said water tank, a connection between the top of the said water tank and the said air chamber, and a spring-pressed valve mechanism having a supply port connected with a source of water supply and having ports, of which one is an open inlet and outlet port and connects with the said water tank, and the other is an outlet port and connects with the flushing rim of the bowl, the said valve mechanism having two valves, of which one controls the said supply port and the other the said outlet port.

3. A water closet, comprising a bowl having a flushing rim, a water tank, an inlet chamber intermediate the said bowl and the said water tank, the said bowl, water tank and inlet chamber being integral and the said inlet chamber having an apertured top and an annular rabbet, and the said inlet chamber having an apertured bottom, and a valve mechanism having a casing within the said inlet chamber and extending through the said apertured top and bottom of the inlet chamber, the upper end of the said casing having a flange seated on the said rabbet, and the said casing having an inlet and an outlet port connecting with the said water tank, and having an outlet port opening into the said inlet chamber, the bottom of the casing having an inlet port, a cap screwing on the lower end of the said casing and against the under side of the said casing bottom, the cap being connected with a source of water supply and two valves having a common spring-pressed valve stem, one of the valves extending into the said cap and controlling the said inlet port and the other valve being within the said casing and controlling the said outlet port.

FRANK SCHUH.
